PRECAST BUILDING SLAB

Dan J. Hurley, Los Angeles, Calif.

Application July 23, 1937, Serial No. 155,280

3 Claims. (Cl. 72—40)

My present invention relates in general to structures of the character used in buildings and relates in particular to a building slab which is pre-cast from suitable plastic or cement-like materials and also to means for securing the slab in place in or as a part of a structure.

It is an object of the invention to provide a unitary slab made from durable and preferably fire-proof material and having peripheral securing elements whereby such a slab or any desired number of them may be secured to a frame or wall structure, such as a floor, inner or outer side wall, roof, or ceiling structure, and whereby adjacent slabs may be secured together. The slabs may be of any size or shape, within reasonable limits, and the thickness of the slab may naturally vary with the character of materials used therein, the size of the slab with relation to the spacing of the supports to which it is secured, and the stresses which must be carried. It is contemplated that rectangular is the peripheral form of slab which will be most extensively used, but other polygonal shapes may be adopted in the practice of the invention in accordance with requirements of structural and artistic design. For example, a very satisfactory artistic effect may be obtained in floors, walls, and ceilings by the use of the slab in hexagonal form.

It is a further object of the invention to provide pre-cast slabs of the character hereinbefore set forth which are especially adapted for use in steel frame structures and which have peripheral securing means of metal adapted to be welded together and also to the steel slab supporting members of the frame structure. The peripheral securing means are imbedded in the peripheral portions of the slabs and are connected by reinforcing means preferably of bar form which extend from each edge of the slab to the opposite edge thereof. Accordingly, the welding together of the peripheral securing means of adjacently placed slabs has also the effect of joining the reinforcing members of one slab with the reinforcing members of the other slab.

It is a further object of the invention to provide pre-cast slabs adapted to be assembled on a frame structure in edge to edge relation, these slabs having metal reinforcing members therein so placed that when the slabs are joined together and to the frame members, the metal reinforcement of the slabs will have the capacity of reinforcement for the frame structure. In the preferred form of the invention the reinforcing means of the slabs include diagonal metal members extending from edge to edge of the slabs

and being so placed that when the slabs are assembled in position on the frame structure these metal members of the slabs will have diagonal reinforcing elements extending from one member of the frame structure to another. Accordingly, where my slabs are employed in a building structure the framework may be of simple form for the reason that the diagonal reinforcement therefor is provided by the metal members contained in the slabs. Otherwise stated, the diagonal reinforcing means of the slabs are tied together and to the vertical and horizontal members of the frame structure so as to become a part of the frame structure, thus making it unnecessary to employ ordinary types of diagonal reinforcement in the frame structure.

It is a further object of the invention to provide slabs of the character above described having means to space the same apart so that spaces will be left between the adjacent slabs, in which spaces welding may be done for the purpose of connecting the slabs together and to the metal members of the frame structure. In the preferred practice of the invention, this spacing means may be, or may constitute a part of, the peripheral securing means. An especial feature of the invention is that adjacent slabs may be secured together at any place along the perimeters thereof, thereby making it possible to use the slabs under conditions where the ideal placing of the structural members and the slabs cannot be followed.

It is a further object of the invention to provide slabs which are economical to make and apply, and which contribute to economy in building construction and which may be used for floors, ceilings, interior and exterior walls, roofs, and column or pilaster construction.

The material from which the body of the slab is made may be generally referred to as "cellular" for the reason that this term will apply to a hardened mass of cement or concrete mixture, to a body made from an aqueous mixture of cement substance and fibrous material, or to a body made by placing granular or fibrous, or mixture of such materials under heavy pressure. Bodies made in the foregoing manners are not truly homogeneous but have minute cell spaces which are filled with air.

Further objects and advantages of the invention will be brought out in the following part of the specification.

Referring to the drawings which are for illustrative purposes only,

Fig. 1 is a partly sectioned perspective view of

a slab embodying the features of my invention.

Fig. 2 is a fragmentary plan view showing a preferred use of the slabs in conjunction with steel frame members, such as floor joists or wall studs of a building frame structure.

Fig. 3 is an enlarged fragmentary section taken as indicated by the line 3—3 of Fig. 1.

Fig. 4 is an enlarged fragmentary section taken as indicated by the line 4—4 of Fig. 2.

Fig. 5 is a view showing a manner in which the space between the slabs depicted in Fig. 1 may be filled.

Fig. 6 is an enlarged fragmentary view of the area indicated by the circle 6 in Fig. 2, the cement material of the slabs being removed so as to clearly show the manner in which the reinforcements of the slabs are connected together and to the frame member by the interconnecting welds.

Fig. 7 is an enlarged fragmentary view of the area indicated by the circle 7 of Fig. 2, this view also having the cement material removed from the metal parts of the adjacent slabs.

Fig. 8 is a fragmentary plan view similar in general character to Fig. 2, but showing how the joints between the slabs may be placed in offset relation to the steel frame members.

Fig. 9 is a fragmentary view of an assembly of slabs, some of these slabs having the surface portions thereof broken away so as to disclose the reinforcement therein, this view showing the manner in which the reinforcing bars of an assembly of slabs cooperate to form the steel reinforcement for the building frame.

Fig. 10 is an enlarged fragmentary section of a peripheral portion of a slab having a part thereof broken away to show an alternative manner of forming and anchoring the peripheral or perimetrical connecting or securing means.

Fig. 11 is a section taken as indicated by the line 11—11 of Fig. 10.

In Fig. 1 of the drawings I show a preferred form of slab 20 embodying the principles of my invention. This slab 20 is preferably of rectangular form, as shown, and is relatively thin as compared with its length and width. It is cast from cementitious material such as, for example, a mixture of aggregate and Portland cement, and for interior or partition wall purposes it may have a considerable proportion of gypsum therein so that it will have light weight, yet sufficient strength for the use to which it is to be put. An especial feature of the invention is that along the periphery thereof it has securing means 21 by which it may be secured in place in a building structure. Although this securing means 21 may be spaced at intervals along the periphery of the slab 20, it is preferably continuous as shown and may be made from a metal bar or rod 22 extending along the side and end faces 23 and 24 of the slab 20, which edge faces define the periphery of such slab 20.

The securing bar 21 is connected to the peripheral portion of the slab 20 by means of suitable anchorage means 25 which may be of a number of different forms, as will be hereinafter described in detail. A simple form of such anchorage means 25 is as shown in Figs. 1 and 3 to 6 inclusive, wherein it is depicted as a bar 26 bent to sinuous or zig-zag form so as to provide inner and outer peaks 27 and 28 disposed in substantially parallel rows along the length of the anchorage member 25. The anchorage member 25 is placed so that the outer row of peaks 28 will engage the bar 22 and so that the inner row

of peaks 27 and a substantial portion of the bar 26 will be within the body of the slab 20. The outer peaks 28 are secured to the bar 22, preferably by welding, this connecting of the members 22 and 25 being preferably accomplished before the slab 20 is cast.

As shown in Figs. 3, 4, 5, and 11, the bar 22 is placed so that it will lie against the lower portions of the edge faces 23 and 24 and so that the lower part of the bar 22 will just touch the plane defined by the under face 29 of the slab 20. This leaves a considerable portion 31 of the edge faces 23 and 24 exposed above the bar 22, and when the slabs 20 are placed in side by side relation, as shown in Figs. 2, 4, and 5, the exposed portions 31 of the edge faces 23 and 24 define side walls of grooves or channels 32 between the adjacent slabs, at the bottoms of which grooves the anchoring or connecting means 21 are situated.

The slab 20 preferably has reinforcing means extending therethrough, and this reinforcing means may be in the form of a metal fabric of some character. In the ordinary practice of the invention I prefer to use diagonal reinforcing bars 33 placed so as to define rectangles or squares. These bars 33 are disposed in crossing relation and the ends 34 thereof are connected to the bar 22 by welding. As best shown in Fig. 4, the bars 33 are spaced above the lower face 29 of the slab 20 and the ends 34 thereof overlie and engage the upper face or portion of the bar 22.

In the preferred practice of the invention, members, such as angles 35 of a building frame structure, are placed as shown in Fig. 2 so that the ends 36 of the slabs 20 will lie in adjacent relation on the exposed faces of the angles 35, and preferably the ends of the slabs of adjacent horizontal rows of slabs are offset so that the grooves 32 defined by the ends 36 of the slabs 20 will not form continuous vertical lines. However, this placing of the slabs so that the ends thereof will rest upon the angles 35 is not always possible and, as shown in Fig. 8, it may be at times necessary to place the slabs 20 with the ends 36 thereof disaligned from the angles 35 which are to support them.

Figs. 4 to 7 inclusive show the manner in which welds 40 may be employed to secure the slabs 20 in place on the building frame structure. Preferably electrical welding is to be employed, and, as shown in Fig. 4, the electrode 41 of an electric welding equipment may be passed down through a groove or channel 32 and, with the underlying angle 35 grounded with the electrical welding circuit, a weld 40 may be made in the position shown, this weld 40 being fused with the angle 35 and the adjacent securing means 21 of the slabs 20. Accordingly, depending on the position of the weld, it may connect bars 22 with an angle 35, as shown in Fig. 4, or it may connect to the angle 35, bars 22, and the ends 34 of diagonal bars 33, as shown in Fig. 6. A weld 40, placed as shown in the circle 6 of Fig. 2 and as shown in Fig. 6, will connect two corners 43 of adjacent slabs 20 with a longitudinal edge 44 of a slab and also to the angle indicated by 35a in Fig. 2. A weld 40', placed as shown in circle 7 of Fig. 2 and as shown in Fig. 7, will connect adjacent edges 45 together and to the underlying angle 35a.

After the desired number of welds 40 have been applied to accomplish the required tying of the slabs 20 to the metal framework, the grooves 32 may be filled with plastic material. As an

example of how the grooves may be filled, I have in Fig. 5 shown a body of packing or caulking material 47 placed in a groove 32 to seal the lower portion thereof and a layer of cement 48 applied over the packing material 47.

In Fig. 9 I show a weld 40b employed to connect bars 33a and 33b together and to a structural member 50. The bar 33b is connected by means of a weld 40c with a diagonal bar 33c which is in turn connected by means of a weld 40d with a metal beam 51 placed perpendicularly with respect to the beam 50. Other sets of diagonal bars 33 of the slabs 20 are connected together by welds 40 and are connected to the members 50 and 51. Accordingly, the diagonal bars 33 of the slabs 20 serve as diagonal reinforcing rods connected directly to the beams of the framework of a structure by welds. In the preferred practice of the invention, the diagonal rods 33 are so placed that the ends 34 thereof are disposed on center lines 53 spaced apart at distances x constituting or forming a division of the distance d at which the beams of the framework, for example, the beams 50 of Fig. 9 or angles 35 of Fig. 2, are spaced, thereby making it possible to readily weld the diagonal bars 33 in end to end relation and to metal members of the framework.

Where there is a random spacing of the ends 36 of the slabs 20 relative to the beams or angles 35, as shown in Fig. 8, many or all of the ends 36 of the slabs may lie in overhanging relation to the beams 35. These overhanging ends 36, however, are not unsupported, for it will be seen that welds 40 connect corners 43 of longitudinally consecutive slabs 20 to the edges 44 of adjacent rows of slabs.

In Fig. 1 I have shown a preferred form of slab 20 which is reinforced so that it will carry loads such as applied to floors, roofs, and exterior walls. There are many uses of the slabs, for instance, as partition walls, wherein material strength is not required in the slabs. In such cases the slabs may be made without internal reinforcement, but merely with peripheral connecting means. Such peripheral connecting

means may be made as shown in Fig. 1 or as shown in Figs. 10 and 11 wherein I show the edge portion of a slab 20c having a bar 22 placed along the periphery thereof, such bar being connected by means of welds 55 to tie or anchoring means consisting of perforated flat plates 56 extending inwardly and upwardly from the edge faces 31 of the slab 20c.

I claim as my invention:

1. A structural member of the character described, comprising a flat slab having a bar extending along the edge thereof and means for connecting said bar to the edge of said slab consisting of a rod bent to sinuous form so as to provide an outer row of peaks which are connected to said bar in such a manner that the sinuous rod will extend from said bar into the edge portion of said slab. 10

2. A structural member of the character described, comprising a flat slab having a bar extending along the edge thereof and means for connecting said bar to the edge of said slab consisting of a rod bent to sinuous form so as to provide an outer row of peaks which are connected to said bar in such a manner that the sinuous rod will extend from said bar into the edge portion of said slab, there being a reinforcing fabric of diagonal bars extending within said slab, the edge of said fabric being connected to said bar. 20

3. A structural member of the character described, comprising a flat slab having top and bottom faces and a peripheral edge face disposed in a plane transverse to the planes of said top and bottom faces, said slab having a bar 35 narrower than said edge face extending along the lower portion of said edge face and means for connecting said bar to said slab consisting of a rod bent to sinuous form so as to provide an outer row of peaks which are connected to said bar in such manner that said sinuous rod will extend into the edge portion of said slab, there being a reinforcing fabric extending within said slab comprising diagonal bars having the ends thereof connected to said first named bar. 40 45

DAN J. HURLEY.
